UNITED STATES PATENT OFFICE.

JAMES S. RAY, OF EAST HADDAM, CONNECTICUT.

DESIGN FOR BURIAL-CASKET HANDLE-SOCKET.

Specification forming part of Design No. **7,100**, dated January 6, 1874; application filed December 27, 1873.
[Term of Patent 7 years.]

To all whom it may concern:

Be it known that I, JAMES S. RAY, of East Haddam, in the county of Middlesex and State of Connecticut, have invented a Design for a Socket for Coffin and Casket Handles, of which the following is a specification:

The nature of this design is fully illustrated in the accompanying drawing, in which—

Figure 1 is a face view of the socket, and Fig. 2 a profile view.

The design consists of a raised cross having inclined concave sides *a a*, terminating at the edge that is contiguous to the coffin or casket in a striated bevel molding, *b b*. The corner portions *c c* of the concave part of the sides of the cross are slightly more prominent than the

intermediate portions *d d*, and, together with the face of the cross, are polished to afford a contrast to the aforesaid portions *d d* of the concave sides, which are rough or frosted, and are embellished with a polished trefoil-leaf extending from a scroll or vine. The striated molding *b* is extended round the lugs, which receive the screws that fasten the socket to the coffin or casket.

What I claim as my invention is—

The design for a socket for coffin and casket handles, substantially as shown and described.

JAMES S. RAY.
